COMBINED LAND AND WATER VEHICLE OR
SIMILAR ARTICLE

Gerard J. Soucy, 16010 Valerio St., Van Nuys, Calif.

Filed Aug. 13, 1959, Ser. No. 57,163

Term of patent 14 years

(Cl. D71—1)

FIG. 1

FIG. 2

FIG. 3

FIG. 4

Fig. 1 is a front elevational view of a combined land and water vehicle, showing my new design,

Fig. 2 is a side elevational view thereof, and

Fig. 3 is a top plan view thereof, and

Fig. 4 is a perspective side view thereof, shown in position for use on water.

The side opposite that shown in Fig. 2 is substantially the same in appearance as that shown, aside from the doors.

I claim:

The ornamental design for a combined land and water

vehicle or similar article, substantially as shown and described.
